CLAIM

We claim the ornamental design for a food heating pellet carrier, as shown and described.

DESCRIPTION

FIG. 1 is a perspective top view of the food heating pellet carrier showing the top, inside and outside thereof.

FIG. 2 is a perspective view showing the bottom and side thereof.

FIG. 3 is a side elevation view wherein all side elevation views are the same.

FIG. 4 is a top plan view; and,

FIG. 5 is a bottom plan view of the food heating pellet carrier.
